UNITED STATES PATENT OFFICE.

COLUMBUS WALTER GLENN, OF KENT, TEXAS.

INSTEP-PLATE FOR SHOES.

1,051,880.

Specification of Letters Patent.

Patented Feb. 4, 1913.

Application filed August 7, 1912. Serial No. 713,934.

To all whom it may concern:

Be it known that I, COLUMBUS WALTER GLENN, a citizen of the United States, residing at Kent, in the county of Culberson 5 and State of Texas, have invented certain new and useful Improvements in Instep-Plates for Shoes, of which the following is a specification.

This invention relates to a protecting plate to be secured beneath the instep or shank of a shoe, through which the wearer of the shoe may apply pressure to a spade or other implement, as in spading dirt, tamping ties, standing on ladders or any kind 15 of work, where pressure is received by that portion of the shoe.

The object of the invention is to provide a protecting plate of this character which will satisfactorily serve the purposes for 20 which it is intended and which will be of light, cheap and durable construction.

The invention accordingly consists in providing a plate of thin, but rigid metal, preferably steel, which is dished 25 or convexed outwardly to present an arched structure and which is provided with a surrounding flange perforated throughout its extent, so that it can be intimately attached to the margin of the 30 shank or instep of the shoe, as well as to the adjoining portion of the shoe tread to rigidly sustain the arched structure against spreading and thus, notwithstanding the thin, light character of the plate, develop 35 the desired rigidity and distribute the pressure received from the spade or other implement of reduced area over the entire area of the plate, so as to prevent discomfort to the wearer or impairment of the 40 shoe. Preferably, the device is provided with a rear wall perpendicular to the plane of the plate and conforming to the front wall of the shoe heel for the combined purpose of protecting the heel and sustaining 45 the plate against creeping on the shoe. The convexed surface of the plate is preferably serrated or roughened to prevent slipping when applied to the implement.

The invention will be fully understood 50 upon reference to the accompanying drawing, in which—

Figure 1 is a perspective view showing

the plate applied, and Figs. 2 and 3 are sections taken respectively on the lines 2—2 and 3—3 of Fig. 1.

1 represents the sole of the shoe; 2 the shank or instep and 3 the heel.

4 represents the improved wearing and protecting plate which is constructed with a marginal attaching flange 4^a with numerous perforations to provide for intimately securing it throughout its extent to the shoe and with its area 4^b within the attaching flange convexed outwardly and provided with serrations 4^c and having at 65 its rear end a vertical wall 4^d conforming to and abutting against the front wall of the shoe heel, and the convexed portion of the plate prevents localizing on any part of the instep, the severe pressure of the reduced portion of the spade or other implement and distributes such pressure throughout the area of the plate. The arched construction also strengthens the plate against bending or indentation and thereby permits the use of very much lighter stock in 70 stamping up the plate. The convex form insures the further advantage of localizing the pressure upon the serrated portion of the plate and preventing contact with the 75 attaching nails which might otherwise soon be worn away or broken off.

I claim:—

A protecting plate for shoes comprising a marginal attaching flange for intimate 85 contact throughout its area with the shoe, a central area convexed outwardly both transversely and longitudinally thereby spacing the central part of the plate from the shoe and preventing pressure on the 90 plate being localized on any part of the instep of the shoe to which it is attached, serrations extending transversely of the convex area, and a vertical wall at one end of the 95 plate adapted to be secured to the heel of a shoe.

The foregoing specification signed at Kent, Texas, this the 30th day of July, 1912.

COLUMBUS WALTER GLENN.
